INVENTOR:

Elias C. Atkins.

UNITED STATES PATENT OFFICE.

ELIAS C. ATKINS, OF INDIANAPOLIS, INDIANA.

AUXILIARY SAW-HANDLE.

SPECIFICATION forming part of Letters Patent No. 287,790, dated November 6, 1883.

Application filed July 18, 1883. (No model.)

To all whom it may concern:

Be it known that I, ELIAS C. ATKINS, a citizen of the United States, residing at Indianapolis, in the county of Marion and State of Indiana, have invented a new and useful Improved Auxiliary Saw-Handle, of which the following is a specification.

My invention relates to an auxiliary saw-handle adapted to be applied at will to that 10 class of crosscut-saw handles which consist, essentially, of a cylindrical bar secured to the end of the saw by a bolt engaging the saw-plate, and passing diametrically through the said bar, and having a nut screwed thereon 15 and against the bar.

The object of my improvement is to provide a loop-shaped handle similar to the handle of an ordinary hand-saw, which may be secured easily and quickly upon the usual crosscut- 20 saw handle of the above-mentioned class at a point opposite the end of the saw, for the purpose of enabling the user to control the movements of the saw more perfectly.

The accompanying drawings illustrate my 25 invention.

Figure 1 is a side elevation of a saw with the ordinary handle and my auxiliary handle attached. Fig. 2 is a perspective of the auxiliary handle.

30 *a* represents the ordinary handle; *b*, a support for the end of the saw; *c*, a bolt adapted to engage the hole usually found near the end of a saw-plate; *d*, a nut screwed on bolt *c*.

e is my auxiliary handle. Said handle has 35 one side, *f*, fitted to the contour of the ordinary handle, *a*, and is provided with a hole, *g*, therein, to receive the end of bolt *c*.

In working a crosscut-saw it is desirable 40 for some purposes to have a firm grip with one hand directly opposite the end of the saw, while the other hand grasps the ordinary han-

dle above the saw; but for other purposes the handle opposite the end of the saw is in the way, and is inconvenient.

I am aware that saw-handles have before 45 been made in which the ordinary cylindrical bar and a loop-shaped handle were formed in one piece, as in the device patented by Abbott & Moss, December 25, 1877. A patent was also granted to me August 26, 1879, for a 50 loop-shaped handle combined, in a peculiar manner, with a cylindrical handle and a fastening for the saw particularly adapted to receive said loop-shaped handle; but my present auxiliary handle differs from either of the 55 above-mentioned patented devices in that it is adapted to be separately manufactured and sold, to be used at will with any saw-handle of the class first mentioned in this specification, it being secured in place on the ordinary han- 60 dle by simply passing the bolt *c* through the hole *g* and screwing on nut *d*, and is as easily removed when its use is not required.

I therefore claim as my invention—

1. As a new article of manufacture, an aux- 65 iliary handle, loop-shaped and having one side adapted to fit against an ordinary crosscut-saw handle, and having a hole in said side adapted to receive a bolt, all substantially as specified.

2. The combination, with an ordinary cross- 70 cut-saw handle, a bolt passing through said handle, and a nut for the purpose of securing said handle to a saw, of a removable auxiliary handle adapted to be secured to said handle by 75 said bolt and nut, substantially as and for the purpose specified.

ELIAS C. ATKINS.
